LATERAL MOTION RESISTANCE AND
CENTERING DEVICE

Albert J. Villano, Schenectady, N. Y., assignor to
American Locomotive Company, New York,
N. Y., a corporation of New York

Application February 2, 1946, Serial No. 645,141

9 Claims. (Cl. 105—189)

1

This invention relates to lateral motion resistance and centering devices.

Lateral motion resistance and centering devices are well known wherein a roller is disposed between two seats, each of which has oppositely inclined runways so that relative lateral motion between the two seats is resisted. In such devices the roller is usually provided with a gear and the seats are provided with inclined racks to assure positive rolling of the roller. Such a conventional device has the drawback that at central or neutral position there is nothing to prevent the roller from oscillating back and forth through a small travel, as when the vehicle in which the device is used is running along a straight path. For example, when a railway vehicle is running along tangent track, the rollers of the lateral motion resistance and centering device oscillate a short distance on either side of their neutral positions, thus permitting a small relative oscillation between the vehicle truck and superstructure. Any considerable relative lateral motion is of course resisted. This freedom to oscillate slightly on tangent track is due to the lack of sufficient initial resistance, usually called break-away resistance, on the part of the roller and is aggravated when the seats between which the rollers are placed become worn at their centers at which time the resistance to roller movement becomes an unknown quantity.

An object of the present invention is to provide a lateral motion resistance and centering device of the type employing rollers between inclined seats wherein a considerable initial break-away resistance at central or neutral position is provided to any initial relative lateral motion between the roller seats.

Another object is to provide a device as aforesaid wherein after the initial break-away resistance is overcome, the resistance to further relative lateral motion between the seats is constant.

Other and further objects of this invention will appear from the following description, the accompanying drawings and the appended claims.

Referring to the drawings forming a part of this application, Figure 1 is a transverse view of a portion of a railway vehicle truck embodying the device of the present invention, partly in section on the line I—I of Fig. 3; Fig. 2 is a longitudinal section of a portion of the truck, taken on the line

2

II—II of Fig. 3; Fig. 3 is a plan of a portion of the structure shown in Fig. 1, parts being removed; Fig. 4 is an enlarged section on the line IV—IV of Fig. 2 showing a roller, and a portion of the seats associated therewith, in neutral or central position; Fig. 5 is a view similar to Fig. 4 showing the seats displaced laterally relative to each other and subject to the initial resistance of the roller; Fig. 6 is a view similar to Fig. 5 but with the seats further displaced at the beginning of the constant resistance of the device; Fig. 7 is an enlarged side view of a gear of the roller of the device; Fig. 8 is an enlarged transverse section through the roller; Fig. 9 is an enlarged fragmentary side view of one of the racks; and Fig. 10 is an enlarged fragmentary sectional view showing one of the roller seats.

The lateral motion resistance and centering device of the present invention, indicated generally by the reference numeral 1, is shown, by way of example, between a center plate 2 and a bolster 3, bolster 3 forming part of a railway vehicle truck 4, the truck having the usual axle 5 and wheels 6. The bolster has a substantially square pocket 7. It will be understood that the device may be associated with other structures besides the truck shown, however.

The device 1 includes a member 8 which is disposed in the pocket 7 and supported by the bolster. The member 8 is an integral casting and includes, at opposite sides of the vertical longitudinal central plane of the truck, seats 9. Each seat 9 has smooth inclined runways 10 converging downwardly and inwardly. At the longitudinal center line of the seat 9, that is at the bottom of the runways and extending longitudinally along the seat, are two spaced ribs 11, each semi-circular in cross section and protruding upwardly one from each of the runways 10, the ribs 11 being spaced by a groove 12 semi-circular in cross-section, so that the curved faces of the ribs 11 are connected by the reentrant curved face of the groove 12. The ribs 11 are also blended into the runways 10 by curved reentrant portions 13. At each end of each seat 9 is a toothed rack 14 which converges downwardly and inwardly from its opposite ends similar to the runways 10.

A roller 15 (Fig. 8) is supported on each seat 9. Roller 15 has a cylindrical face 16 extending entirely around the roller 15 except at its bottom

where it is interrupted by two longitudinal spaced grooves 17 semi-circular in cross section and connected by a rib 18 semi-circular in cross section, the face of the rib 18 forming a reentrant curve connecting the faces of the grooves 17. The faces of the grooves 17 are blended into the face 16 by curved reentrant portions 19. As shown in Figs. 8 and 10, the radii r and r' of grooves 17 and ribs 11 respectively are equal.

The grooves 17 are spaced apart a distance equal to the distance that the ribs 11 are spaced apart, and the rib 18 is of a size adapting it to be disposed in the groove 12 without touching the bottom thereof. The roller 15 has gears 20 at its opposite ends disposed in the adjacent racks 14. The roller is disposed at its neutral or central position (Fig. 4) with its rib 18 in groove 12 and with its grooves 17 receiving the ribs 11, the engagement between the roller 15 and the seat 9 being at the uppermost portions of the ribs 11 which engage the adjacent portions of the grooves 17. Thus the roller 15 has a two-point support on the seat 9 and the face 16 is out of engagement with the runways 10.

A member 21 is mounted on top of the rollers. It is a casting and, similar to the casting 8, it has seats 22 which have runways 23 converging upwardly and inwardly but have at their longitudinal central portion a curved part 24 substantially corresponding to the portion of the face 16 which they engage. Toothed racks 25 are provided at the ends of seats 22. The center plate 2 is bolted to the member 21.

As will be seen from Fig. 1, when the center plate is in central position, the two rollers 15 are in neutral or central position, that is they rest on the ribs 11 (Fig. 4) and the portions 24 engage the tops of the rollers 15. Each roller 15 thus has a three-point bearing, its engagement with its correlated portion 24 being one point, and its engagement with the two ribs 11 being the other two points.

The device 1 offers considerable initial resistance (break-away resistance) to any relative lateral motion between the center plate 2 and the bolster 3 whether this relative lateral motion tends to take place on tangent track or on a curve. Before such relative lateral motion can occur between the center plate 2 and the bolster 3, that is between the seats 9 and 22, the two-point support of each roller 15 must be disturbed and the stability of this two-point support overcome. The effect of this can be understood by comparison with a conventional lateral motion resistance and centering device wherein the roller has a continuous cylindrical face and engages at its top and bottom, seats similar to the seat 22. Such a conventional roller would tend to rock easily in the portions in the top and bottom seats corresponding to portion 24, and this would be especially true where these portions become worn in service.

In the instant device before seats 9 and 22 can be laterally displaced relative to each other, each roller must be disturbed from its two-point support on the ribs 11, and it will take a considerable shock to do this. That arcuate portion of each of the ribs 11 which engages the corresponding arcuate portions of the grooves 17 in the roller 15 will oppose the lateral movement of the roller. Therefore slight disturbances which in conventional structures cause relative lateral motion between the center plate and the bolster will not cause relative lateral motion between the center plate 2 and the bolster 3 where the device 1 is employed.

When the force tending to cause relative lateral motion between the center plate 2 and the bolster 3 is considerable, the two-point support of each of the rollers 15 will be overcome and as soon as they 5 are overcome the faces 16 of the two rollers will engage the smooth inclined runways 18 and 23 of the roller seats and thereafter the device will 10 act like a conventional lateral motion resistance device, offering constant resistance as the lateral motion continues. Such considerable relative lateral motion will usually take place on a curve.

When the truck returns to tangent track from a curve, then the device 1 urges the center plate 2 and the bolster 3 back to their neutral or central position as shown in Fig. 1 as the rollers roll 15 down the inclined runways and permit the center plate 2 to approach the bolster 3.

Referring to Fig. 6 and assuming that now the roller is returning to neutral or central position, it will be seen that as the face 16 leaves the runway 10 the roller will drop quickly into place on the two ribs 11 so that the last part of the return relative lateral motion is effected by a quick snap which places the roller back in its three-point bearing position. The gears and racks assure 25 that when the roller reaches its neutral or central position the ribs 11 will be disposed in the grooves 17.

From the foregoing it will be seen that a lateral motion resistance and centering device has been 30 provided which strongly resists initial relative lateral motion and will prevent any relative lateral motion at all when the inducing forces are substantially as when the vehicle is running on tangent track, and this resistance will only be overcome 35 when the inducing force is large as when the vehicle is entering curved track. Furthermore as soon as the initial resistance is overcome, that is when the parts are in the position shown in 40 Fig. 6, then thereafter the roller engages the seats only on its cylindrical face 16 and a constant resistance is offered to further relative lateral motion.

The roller may be made in various ways. In 45 the instant case it is shown made of two separate parts 15a and 15b in flush engagement at their inner ends on the transverse center line of the pocket 7 and welded at their outer ends to their gears 20. Each of the parts 15a and 15b has a central bore 26 and a counterbore 26a in which is 50 disposed a dowel bar 27 which laps the joint between the two parts. No patentable significance is to be attached to this particular two-piece construction of the roller. The roller has been so 55 constructed of two pieces and an aligning dowel solely to facilitate assembly in the railway vehicle to which it is applied. An integral roller would function equally well.

While there has been hereinbefore described 60 an approved embodiment of this invention, it will be understood that many and various changes and modifications in form, arrangement of parts and details of construction may be made thereto without departing from the spirit of the invention, and that all such changes and modifications as fall within the scope of the appended claims are contemplated as a part of this invention.

The invention claimed and desired to be secured by Letters Patent is:

70 1. A lateral motion resistance and centering device comprising two opposed normally centralized roller seats, one of the seats having two lateral inclined runways diverging from their adjacent inner ends toward the other of the seats; 75 and a roller between and in engagement with the

seats, the engaging portions of the roller and of the seat with the inclined runways having co-acting means to provide mutual lateral engagement between such portions, when such seats are centralized, said means including two laterally spaced depressions in one of the engaging portions and two laterally spaced projections on the other of such portions, the projections being normally disposed in the depressions whereby a force initially moving one of the seats laterally relative to the other of the seats must first overcome the resistance resulting from the engagement between the depressions and projections.

2. A lateral motion resistance and centering device comprising two opposed normally centralized roller seats, one of the seats having two lateral inclined runways diverging from their adjacent inner ends toward the other of the seats; and a roller between and in engagement with the seats, the engaging portions of the roller and of the seat with the inclined runways having coacting means to provide mutual lateral engagement between such portions, when such seats are centralized, such means including two laterally spaced grooves in one of the engaging portions and two laterally spaced ribs on the other of the portions the ribs being normally disposed in the grooves whereby a force initially moving one of the seats laterally relative to the other of said seats must first overcome the resistance resulting from the engagement between the grooves and ribs.

3. A lateral motion resistance and centering device comprising two opposed normally centralized members, each having two laterally spaced roller seats, the seats of one of such members each having two lateral inclined runways diverging from their adjacent inner ends toward the correlated seat of the other of such members; and a roller between and in engagement with each of the correlated seats, the engaging portions of each of the rollers and its inclined runways, when such members are centralized, having coacting means providing mutual lateral engagement between such portions, said means including two laterally spaced depressions in one of such portions and two laterally spaced projections on the other of such portions normally disposed in such depressions whereby a force initially moving one of the members laterally relative to the other of the members must first overcome the resistance against movement of the rollers.

4. A lateral motion resistance and centering device comprising two opposed normally centralized roller seats, each of the seats having two lateral inclined runways diverging from their adjacent inner ends toward the other of the seats; and a roller between and in engagement with the seats, the roller and one of the seats, when the seats are centralized, having coacting means providing lateral engagement there between, said means including two laterally spaced grooves in the roller and two laterally spaced ribs on the seat normally disposed in the grooves whereby a force initially moving one of the seats laterally relative to the other of the seats must first overcome the resistance against movement of the roller resulting from the engagement between the grooves and the ribs.

5. A lateral motion resistance and centering device comprising two opposed normally centralized roller seats, each of the seats having two lateral inclined runways diverging from their adjacent inner ends toward the other of the seats; and a cylindrical roller between and in engagement with the seats, the roller and one of said

seats, when said seats are centralized, having co-acting means providing lateral engagement therebetween, said means including two laterally spaced grooves semi-circular in cross section in said roller and two laterally spaced ribs semi-circular in cross section on the coating seat, such ribs being normally disposed in the grooves whereby a force initially moving one of the seats laterally relative to the other of the seats must first overcome the resistance against movement of the roller resulting from the engagement between the grooves and ribs, the grooves being connected to each other and to the cylindrical face of the roller by reentrant curved portions and the ribs being connected to each other and to their connecting runways by reentrant curved portions.

6. A lateral motion resistance and centering device comprising opposed lateral roller seats, one of the seats having runways diverging from their adjacent inner ends toward the other of the seats, the angle of inclination of each runway being constant; and a roller between the seats disposed, when the seats are centralized relative to each other, at the bottom of the runways, the engaging portions of the roller and the runways, when the roller is in such bottom position having means providing lateral engagement therebetween, such means including two laterally spaced grooves in one of the portions extending in a direction longitudinally of the roller, and two laterally spaced ribs on the other of the portions normally disposed in the grooves, the roller having a cylindrical face extending from one outer side of its said portion completely around the roller to the other side of its said portion and engaging such other seat, whereby initial relative lateral movement between the seats from their centralized position is resisted by the stability of such lateral engagement, and further relative lateral movement between the seats, after such initial relative lateral movement, is opposed by constant resistance emanating from the movement of the roller cylindrical face along one of the constantly inclined runways.

7. A lateral motion resistance and centering device comprising two opposed roller seats, one of the seats having inclined runways diverging outwardly toward the other seat and having a plurality of longitudinal ribs thereon; and a roller having a cylindrical periphery with a plurality of longitudinal grooves therein, said roller being disposed between the seats so that the grooves therein will engage the seat ribs when the roller is at the bottom of the inclined runways whereby a force initially moving one of the seats laterally relative to the other of the seats must first overcome the resistance against movement of the roller created by the engagement of grooves and ribs.

8. A lateral motion resistance and centering device arranged between the truck element and the load element of a railway vehicle comprising two opposed roller seats, one disposed upon the truck element and one upon the load element, the truck element seat having inclined runways diverging outwardly from its center line toward the other seat and having longitudinal ribs spaced from said center line; a roller arranged between the seats in engagement therewith and normally disposed upon the center line of the truck element seat, said roller having longitudinal grooves in engagement with the seat ribs when the roller is in normal position, whereby a force initially moving one of the seats laterally relative to the

other must first overcome the resistance against movement of the roller resulting from the engagement between the grooves and the ribs; a pinion upon the roller; and a rack on one of said elements to mesh with the pinion to maintain the grooves of the roller in predetermined positions relative to the ribs of the seat.

9. A lateral motion resistance and centering device, according to claim 8, in which the normally engaging portions of the grooves and ribs 10 have curvatures of the same radius.
